UNITED STATES PATENT OFFICE.

MALCOLM E. LAUNBRANCH, OF CHICAGO, ILLINOIS, ASSIGNOR TO PEERLESS ELECTRIC SIGN COMPANY, OF CHICAGO, ILLINOIS, A CORPORATION OF ILLINOIS.

ELECTRIC-SIGN SYSTEM.

1,235,818.

Specification of Letters Patent. Patented Aug. 7, 1917.

Application filed January 22, 1916. Serial No. 73,593.

To all whom it may concern:

Be it known that I, MALCOLM E. LAUNBRANCH, a citizen of the United States, residing at Chicago, in the county of Cook and State of Illinois, have invented a certain new and useful Improvement in Electric-Sign Systems, of which the following is a full, clear, concise, and exact description, reference being had to the accompanying drawings, forming a part of this specification.

My invention relates to electric signs and more particularly to that class of signs in which there are a plurality of units, each of which units has a plurality of electric lamps, for instance, so disposed that a judicious selection of the lamps will enable the unit to display any letter of the alphabet or other desired character. The sign thus is constructed to display different words successively or even entire sentences if there are enough units for that purpose.

My invention concerns itself with the controlling mechanism to control the selection of the lamps so that a predetermined word or sentence may be displayed upon the sign. My invention concerns itself also with the mechanism for causing a rapid change in the legend displayed upon the sign.

In the specification herein and in the claims I use the word "lamp" to signify some individual device capable of performing the functions herein.

Certain control features of my invention herein are a simplification of the templet control broadly set forth in my co-pending application Serial No. 73,594, filed Jan. 22, 1916.

Each unit of the sign has preferably fifty-three lamps which I have found are sufficient to portray at least forty letters or characters, and that meets the ordinary requirements.

I will explain one form of control apparatus for controlling a sign of the above class more in detail by referring to the accompanying drawings, in which—

Figure 1 is a side view of a control apparatus constructed in accordance with my invention, portions being broken away and omitted more clearly to reveal features of construction;

Fig. 2 is a fragmentary top view of the relay control apparatus;

Fig. 3 is a fragmentary side view thereof;

Fig. 4 is a fragmentary side view of the structure shown in Fig. 1;

Fig. 5 is a fragmentary sectional view illustrating the contacting elements;

Fig. 6 is a diagrammatic view illustrating the templet style of control;

Fig. 7 is a detail perspective view of an automatic circuit controlling element;

Fig. 8 is a more or less diagrammatic view illustrating the circuit connections to the lamps;

Fig. 9 is a perspective view illustrating the framework construction;

Fig. 10 is a fragmentary view of a templet;

Fig. 11 is a fragmentary sectional view showing the spring pressed plunger structure, and

Fig. 12 is an elevation of the electromagnetic device shown in Fig. 6.

Referring more particularly to Figs. 1 and 4, I show a base plate 1 which carries a stationary framework 2, which stationary framework has the legs 3 and end strips 4, top strips 5, and bottom strips 6. These strips 5 and 6 in each case include a channel and a bar. This stationary framework carries a plurality of channel members 7 at the top and the bottom into which suitable

self-contained unit structures 8 may be slid and held in place. These unit structures 8 are shown most clearly in Figs. 1 and 4 and consists of bottom strips 9, side strips 10 and 11, top strip 12, and cross pieces 13 and 14.

A further cross piece 15 is also provided. Legs 9^a projecting from angle pieces 9 slide in the channels 7 and the upper extremities of the end rods 10 and 11 slide in the channels 16. Thus each self-contained structure 8 may be removed as is desired.

The structure 8 carries a plurality of metallic bars 17, there being preferably fifty-three, so that one bar is connected to one of the lamps in a given unit of the sign, each structure 8 corresponding to one unit of the completed sign. These contact rods 17 are stationarily and insulatingly mounted in the framework 8 and coöperate with contacts 18 as more clearly shown in Fig. 5.

These contacts 18 are carried by slidable rods 19, which slidable rods are slidably mounted in the framework 8. Each

sliding rod 19 has its contacts 18 arranged in different positions and each sliding rod 19

slide in the channels 16. Thus each self-contained structure 8 may be removed as is desired.

The structure 8 carries a plurality of metallic bars 17, there being preferably fifty-three, so that one bar is connected to one of the lamps in a given unit of the sign, each structure 8 corresponding to one unit of the completed sign. These contact rods 17 are stationarily and insulatingly mounted in the framework 8 and coöperate with contacts 18 as more clearly shown in Fig. 5.

These contacts 18 are carried by slidable rods 19, which slidable rods are slidably mounted in the framework 8. Each

sliding rod 19 has its contacts 18 arranged in different positions and each sliding rod 19

slide in the channels 16. Thus each self-contained structure 8 may be removed as is desired.

The structure 8 carries a plurality of metallic bars 17, there being preferably fifty-three, so that one bar is connected to one of the lamps in a given unit of the sign, each structure 8 corresponding to one unit of the completed sign. These contact rods 17 are stationarily and insulatingly mounted in the framework 8 and coöperate with contacts 18 as more clearly shown in Fig. 5.

corresponds to a given letter or character. Thus one selecting rod 19 may correspond to the letter "a," the next one to the letter "b," and so on. Normally the strips are in a position where contact is not established as shown for instance in Fig. 5. A sliding framework to be presently described is then employed to move one of the rods 19 into its contact making position to establish a 10 certain letter or character in that particular unit of the sign to which it corresponds.

This sliding framework is rectangular in form, having the rectangular section consisting of the strips 20, 21, 22 and 23 on 15 both extremities and having the connecting strips 24 and 25 on both sides as readily apparent. This framework has guide members 26, 26 so that it may slide upon rails 27, 27. An eccentric 28 operates the eccentric 20 rod 29 to slide this movable framework and the arrangement is such that for each operation the eccentric 28 makes one complete revolution of 360 degrees.

Referring more particularly to Fig. 1, 25 the movement of the sliding framework first consists of a slight movement toward the left, then a movement toward the right beyond its starting position, and then back a slight distance to the left to its normal position as shown in Fig. 1. As before stated, 30 a contact rod 19 must be displaced out of its position in order to establish a letter, and the first movement of the framework is calculated to restore any rod 19 which is so 35 displaced. The movement of the framework to the right then sets another rod 19 previously selected into its contact making position, and the return movement of the framework to normal restores the setting 40 mechanism to normal without restoring the rod as the framework has not come back far enough to again restore this set rod. The rods extend as far as the uppermost rod 19 in Fig. 1 and the sliding framework has a 45 plate 30 which restores the rods to normal position, the upper rod 19 in Fig. 1 being shown in its normal non-contact making position. If the said rod 19 were in its contact making position, its right hand extremity would rest against the plate 30 when 50 the framework is in the normal position as shown in Fig. 1. I utilize electromagnetic means to set the rods and these electromagnetic means include the electromagnets 31 of 55 which there are as many as there are rods 19, these electromagnets being mounted upon the side strips 20. These electromagnets have armatures 32 which are normally not in the path of the rods 19. Immediately 60 any electromagnet 31 is energized, its armature is attracted into the path of the rod 19 as will be more clear from Fig. 3, whereupon a movement of the sliding framework to the right will cause the corresponding 65 rod 19 to be set into its circuit closing posi-

tion. Then when the sliding framework comes back to normal position (where as yet it is not in position to restore the set rod 19) then the armatures 32 are of course again all in their position shown in the figures 70 without projecting farther toward the right than the left hand extremity of the unset rods 19. The set rod 19 however stays in its circuit closing position until a further cycle of movement of the sliding framework, at which time the set rod 19 is first restored and then possibly some other rod 19 corresponding to a different character or letter is set due to the previous selection of another electromagnet 31. There are of 80 course as many electromagnets as there are rods 19 so that there may be forty electromagnets for each sign unit if it were desired to have that many characters available for each sign unit. 85

Now in order to set the desired electromagnets 31 I utilize a platen 33 which cooperates with a templet 34 and spring pressed plungers 35. Each contact plunger 35 extends to a magnet 31. The templet 34 90 is perforated to correspond to the particular electromagnet 31 of each unit or structure 8 that it is desired to operate. The circuit then extends (Fig. 6) from the electromagnet 31 by way of conductor 36, through 95 the battery 37, conductor 38, platen 33, protruding contact 35, conductor 39, to the electromagnet 31. It will be seen from the illustration that only those electromagnets 31 are energized for which a hole has been 100 punched in the templet 34. The platen 33 is preferably of magnetic material so that it may be held in position against an electromagnet 40 when it is in its circuit closing position, this electromagnet having a coil 105 supplied with current likewise from the battery 37. The circuit for this electromagnet may then extend from the battery 37 by way of conductor 42, contact elements 43, and 44, conductor 45, magnet 40, conductor 46, contact 47, contact 48, platen 33, conductor 38, to the battery 37. The object of thus locking the platen in position is due to this. Assume that it is desired to set up 110 a certain legend upon the sign, then a templet 34 is inserted which corresponds to a given letter of each unit. The platen 33 is then closed and magnetically held in its closed position so that the selected electromagnets 31 remain energized. The shaft 115 carrying the eccentric 28 is then started in operation to make one revolution and the electromagnets of course must remain energized throughout the setting operation of the corresponding rods 19. A crank 55 is 120 shown to indicate means for rotating the said shaft. As soon as the setting operation has been completed and when the movable framework is on its back stroke toward its 125 normal position, contact is broken between 120 and 125

the contacts 43 and 44 so that the electro-magnets are in their unenergized condition and the platen pulled back to its open position by means of gravity against the cushion 49. The means by which this circuit between the elements 43 and 44 is broken consists of the yielding insulating finger 50 which is mounted upon the strip 23 of the movable framework, the contacts 43 and 44 being mounted upon any part of the stationary framework. The operation of this device will be clear from Fig. 7 when it is stated that the contact finger 50 moves over on top of the contact 44 when the said finger 50 moves toward the right from its initial position, thereby not disturbing the contact between these two elements; when the framework moves in the opposite direction the finger 50 passes between the elements 43 and 44 to momentarily break the circuit, the finger 50 being shown in the illustration (Fig. 7) as having just passed between the elements 43 and 44 but not having as yet completed its entire movement to the left beyond the contact spring 44. It will thus be understood that the movable framework makes one complete cycle of movement whereby the insulating finger 50 (Fig. 7) normally starts from a position slightly to the left of the spring 44. The first movement of the movable frame carries the finger 50 to the right, riding over the spring 44 until it reaches a position beyond the spring 44, whereupon the movable framework moves to the left carrying the insulating finger 50 between the springs 44 and 43, thus breaking the circuit of the magnet 40, whereupon the said finger moves to the left as far as the framework moves, and then moves back toward the right slightly to its normal resting place, which as before stated is slightly to the left of the spring 44. As will be clear of course the armatures 32 normally do not touch the bars 19 when these bars are in their normal non-contact making position, it requiring a positive movement toward the right (Fig. 1) of the movable framework before the armatures 32 displace the rods 19.

From what has been described it is thought the nature of my invention will be readily clear to those skilled in the art, as will also its various modifications. Having however thus described one form which my invention may take, what I claim as new and desire to secure by Letters Patent is:

1. In a device of the character described the combination with a plurality of lamps adapted when selectively actuated to portray unlike characters, means for controlling the selection of desired lamps to portray unlike characters, said means including a plurality of character elements, a movable framework, electromagnetic means carried by said framework adapted when actuated to control said character elements, a templet for controlling the selection of said electromagnetic means, a stationary

tuated to control said character elements, and a templet for controlling the selection of said electromagnetic means.

2. In a device of the character described the combination with a plurality of lamps adapted when selectively actuated to portray unlike characters, means for controlling the selection of desired lamps to portray unlike characters, said means including a plurality of character elements, a movable framework, and electromagnetic means carried by said framework adapted during movement of said framework to control selected character elements corresponding to actuated electromagnetic means aforesaid, a templet for controlling the selection of said electromagnetic means, and means movable with said framework for controlling said electromagnetic means.

3. In a device of the character described the combination with a plurality of lamps adapted when selectively actuated to portray unlike characters, means for controlling the selection of desired lamps to portray unlike characters, said means including a plurality of slidable character elements, a movable framework, and electromagnetic means carried by said framework adapted when actuated to control said character elements, said electromagnetic means including armatures adapted to be thrust into the path of said character elements, and a templet for controlling the selection of said electromagnetic means.

4. In a device of the character described the combination with a plurality of lamps adapted when selectively actuated to portray unlike characters, means for controlling the selection of desired lamps to portray unlike characters, said means including a plurality of slidable character elements, a movable framework, and electromagnetic means carried by said framework adapted during movement of said framework to control selected character elements corresponding to actuated electromagnetic means aforesaid, said electromagnetic means including armatures adapted to be thrust into the path of said character elements, a templet for controlling the selection of said electromagnetic means, and means movable with said framework for controlling said electromagnetic means.

5. In a device of the character described the combination with a plurality of lamps adapted when selectively actuated to portray unlike characters, means for controlling the selection of desired lamps to portray unlike characters said means including a plurality of character elements, a movable framework, and electromagnetic means carried by said framework adapted when actuated to control said character elements, a templet for controlling the selection of said electromagnetic means, a stationary

framework relative to which said movable framework moves, and a third framework removably mounted in said stationary framework for carrying said character elements.

6. In a device of the character described the combination with a plurality of lamps adapted when selectively actuated to portray unlike characters, means for controlling the selection of desired lamps to portray unlike characters, said means including a plurality of character elements, a movable framework, and electromagnetic means carried by said framework adapted during movement of said framework to control selected character elements corresponding to actuated electromagnetic means aforesaid, a templet for controlling the selection of said electromagnetic means, means movable with said framework for controlling said electromagnetic means, a stationary framework relative to which said movable framework moves, and a third framework removably mounted in said stationary framework for carrying said character elements.

7. In a device of the character described the combination with a plurality of lamps adapted when selectively actuated to portray unlike characters, means for controlling the selection of desired lamps to portray unlike characters, said means including a plurality of slidable character elements, a movable framework, and electromagnetic means carried by said framework adapted when actuated to control said character elements, said electromagnetic means including armatures adapted to be thrust into the path of said character elements, a templet for controlling the selection of said electromagnetic means, a stationary framework relative to which said movable framework moves, and a third framework removably mounted in said stationary framework for carrying said character elements.

8. In a device of the character described the combination with a plurality of lamps adapted when selectively actuated to portray unlike characters, means for controlling the selection of desired lamps to portray unlike

characters, said means including a plurality of slidable character elements, a movable framework, and electromagnetic means carried by said framework adapted during movement of said framework to control selected character elements corresponding to actuated electromagnetic means aforesaid, said electromagnetic means including armatures adapted to be thrust into the path of said character elements, a templet for controlling the selection of said electromagnetic means, means movable with said framework for controlling said electromagnetic means, a stationary framework relative to which said movable framework moves, and a third framework removably mounted in said stationary framework for carrying said character elements.

9. In a device of the character described the combination with a plurality of lamps adapted when selectively actuated to portray unlike characters, means for controlling the selection of desired lamps to portray unlike characters, said means including a plurality of character elements, a movable framework, and electromagnetic means carried by said framework adapted during movement of said framework to control selected character elements corresponding to actuated electromagnetic means aforesaid.

10. In a device of the character described the combination with a plurality of lamps adapted when selectively actuated to portray unlike characters, means for controlling the selection of desired lamps to portray unlike characters, said means including a plurality of character elements, a movable framework, electromagnetic controlled means carried by said framework adapted when actuated to control said character elements, and a templet for controlling the selection of said electromagnetic controlled means.

In witness whereof, I hereunto subscribe my name this 17th day of January, A. D., 1916.

MALCOLM E. LAUNBRANCH.
